Primary Examiner — Catherine S Posthauer(74) *Attorney, Agent, or Firm* — Cantor Colburn LLP**CLAIM**

The ornamental design for a handle for home appliance, as shown and described.

DESCRIPTION

FIG. 1 is a front perspective view of a handle for home appliance, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion 8 in FIG. 1;

FIG. 9 is a cross-sectional view taken along the line 9-9 of FIG. 2;

FIG. 10 is a perspective view as shown in a user environment; and,

FIG. 11 is a perspective view as shown in another user environment.

The evenly broken lines are shown for the purpose of illustrating environmental subject matter of exemplary appliances and handles. The dot-dash broken lines represent the designation of enlargement views. None of the broken lines form part of the claimed design.
